UNITED STATES PATENT OFFICE.

FRED A. BREY, OF DEL NORTE, COLORADO.

LETTER-OPENER.

1,306,945.

Specification of Letters Patent. Patented June 17, 1919.

Application filed March 31, 1919. Serial No. 286,261.

To all whom it may concern:

Be it known that I, FRED A. BREY, a citizen of the United States, residing at Del Norte, in the county of Rio Grande and State of Colorado, have invented certain new and useful Improvements in Letter-Openers, of which the following is a specification.

This invention relates to devices for cutting or opening envelops and the like, having for its primary object to provide a cutting implement of simple and inexpensive construction which is of small compass so as to enable the same to be conveniently carried in the pocket, and which may, if desired, be attached to an ordinary key ring.

A further object of the invention is to provide an envelop opener which has its cutting edges so disposed as to obviate the possibility of cutting the hands during the opening operation, and which precludes the possibility of the cutting edges engaging the pocket or clothing.

A still further object is to provide a cutting implement of the character stated which is constructed in such manner that an envelop may be easily and quickly operated upon and which permits only a very small amount of the envelop edge entering between the cutting blades, whereby the contents of the envelop are protected against becoming cut or damaged.

The invention has for a still further object to provide an envelop cutting implement having improved cutting blades associated therewith, and which blades are arranged in such manner that the same may be easily removed from the holder for sharpening or replacing.

A still further object is to provide a device of the class described having its co-operating blades so arranged as to exert increased cutting pressure upon envelops or paper of increasing thickness, whereby the cutting operation for such thickness is facilitated without additional physical exertion.

With these objects in view, together with others which will appear as the description proceeds, the invention resides in the novel construction, combination and arrangement of parts, all as will be described more fully

hereinafter, illustrated in the drawings, and particularly pointed out in the claims.

In the drawings:

Figure 1, is a perspective view, on an enlarged scale, of a cutting implement constructed in accordance with the invention,

Fig. 2, is a top plan view of the improved cutter, and

Fig. 3, is an end view, parts broken away, of the cutter, and showing the application of an envelop thereto.

Referring now more particularly to the drawing, 4 indicates the body portion of my improved cutter, and 5 the handle thereof. The cutter body and handle are preferably formed of a single piece of thin sheet metal, and if the device is constructed as shown the holder may be stamped. The body part comprises a piece of metal of rectangular shape, bent upon itself at its medial portion as at 6, and the ends of the portion are flared or arranged in divergent relation to provide blade holding wings 7. The handle 5 is connected to the body in such manner as to extend parallel with the bended or folded portion of the body plate, and the handle may be enlarged at its outer end to enable the said end to be secured to a suitable support. The end of the handle in the present instance is apertured as at 8, to enable the same to be attached to a key ring.

The cutting blades of the implement are indicated at 9, and these blades are to be secured to the wings of the holder in such manner that the sharpened edges thereof meet, or substantially meet, over the space between the said wings. The blades are straight throughout approximately their entire length and are of equal length with their supporting wings. Each blade is provided with an angularly disposed base portion 10, through which screws or retaining rivets 11 are driven to secure the blades to the wing portions. It will be observed, particularly with reference to Figs. 2 and 3, that the cutting blades lie in the same plane, and firmly rest upon the upper edges of the wings 7, and the sharpened edges of these blades are disposed a relatively short distance above the bottom of the base channel formed between the wings. This particular

arrangement permits of a letter being placed between the cutting blades and resting in the groove or channel without the blades extending any appreciable distance beyond the 5 envelop edge.

The forward ends of the cutting edges are curved as at 13, whereby the insertion of an envelop between the cutting edges is facilitated.

- 10 In practice, the envelop is held with one end resting in the groove between the wings 7. The handle is grasped in one hand, the milled or roughened portion 14 on the handle permitting the fingers obtaining a firm 15 grip, while the envelop is held with the other. Movement of the envelop and cutting device toward each other will cause the envelop edge to pass between the cutting blades and the sharpened edges will engage 20 the envelop inwardly from the edge thereof a slight distance and will cause a clean severance. The line of cut will always be parallel with the envelop edge, as the envelop rests in the groove at the meeting portions 25 of the wings 7. Should the blades become dull, the screws or rivets 11 may be easily removed so as to permit of the blades being detached, and the blades may be replaced or resharpened. By assembling the blades 30 upon the wings in the manner set forth, it

is obvious they will not be subjected to undue strain, as the strains will be evenly distributed to the supporting wings 7.

While the above is a description of the preferred form of the invention it is to be understood that the invention is not limited thereto, as various changes may be made in the minor details of construction and arrangement of parts without departing from the invention as defined by the claims. 35 40

I claim:—

1. In a device of the class described, a body comprising a plate bent upon itself and providing divergent wings, blades carried by said wings and projecting toward each 45 other and having their cutting edges substantially meeting equidistant between the said wings, the said cutting edges curved outwardly near one end, and means for holding the said blades upon said wings. 50

2. In a device of the class described, a body comprising a plate bent upon itself and providing divergent wings, cutting blades comprising bodies bent angularly and adapted to fit upon said wings, screws for attaching said blade bodies upon said wings, and the cutting edges of said blades projecting from said wings toward each other. 55

In testimony whereof I affix my signature.
FRED A. BREY.
